UNITED STATES PATENT OFFICE

2,076,269

COVERING APPARATUS

Thomas Harris, Providence, R. I., assignor to
 Harris Textile Machinery Corporation, a
 corporation of Rhode Island

Application August 22, 1934, Serial No. 740,955

15 Claims. (Cl. 117—40)

This invention relates to a covering apparatus, and has for one of its objects the covering of a core or filament with untwisted fibers wrapped helically about the core.

Another object of the invention is the delivery of a wrapping material to a core and controlling the amount and size of the material to be wrapped with reference to the advancing and rotating movement of the core so as to control many factors with reference to the character of the wrap required.

Another object of the invention is to control the width of the wrapping material through the control of the amount which is delivered to the core at the point of wrapping.

Another object of the invention is to control the tension applied to the covering by the speed with which the wrapping material is delivered to the core at the point of wrapping.

Another object of the invention is to control the tension on an elastic core, such as a core of soft elastic by means of a differential drive so that the tension may be varied with reference to the rotative movement of the core about its own axis of feed.

Another object of the invention is to control the delivery of the wrapping material so as to govern how tight it shall be wound upon the core, this factor varying with reference to the circumference of the core upon which the material is to be wrapped.

With these and other objects in view, the invention consists of certain novel features of construction, as will be more fully described, and particularly pointed out in the appended claims.

In the accompanying drawings:

Fig. 1 is a schematic sectional view illustrating the principal parts of the apparatus and their relations one to the other;

Fig. 2 is a sectional view on line 2—2 of Figure 1;

Fig. 3 is a sectional view on a larger scale of the filer head;

Fig. 4 is an end view illustrating the gearing arrangement for the differential drive of the filer head;

Fig. 5 is a view along the line of Figure 1 of a modified arrangement of the apparatus; and

Fig. 6 is a view of the core which has been covered in the apparatus.

In covering apparatus, I have found that it is frequently desirable to control the width as well as the amount of the covering material which is to be helically wound upon a core; and in such connection, I have used an apparatus as disclosed

in my Patents 1,922,549 or 1,922,950, by which I may deliver untwisted fibers in the size desired, and by rotating a core in adjacency to the delivery end of such apparatus, I may wrap this material about the core, and by the use of this spinning unit, I may so nicely control the delivery as to speed and amount of the material to be wrapped about the core that I may place on the core the desired covering.

And in addition to this spinning apparatus, I have developed a differential control for the feed of core with reference to its rotation by which I may not only rotate the core on its own axis, but I may feed it at varying speeds with reference to such rotation by which I may additionally control and secure the desired character of wrapping which I desire; and the following is a more detailed description of the present embodiment of the invention, illustrating the preferred means by which these advantageous results may be accomplished:

With reference to the drawings, in Figure 1, I have designated at 10 a spinning unit substantially as shown in my above mentioned patents. Gearing is provided as shown in these patents (see Figure 3 of Patent No. 1,922,949) for driving and varying the drive of the independent deck units and rolls thereon so as to govern the amount of reduction and speed of delivery of a sliver designated at its upper end 11 and at its delivery end as 12 to form the covering material to be wrapped about a core 13. By reason of the delivery rolls 14 of my unit 10 being fixed, no twist additional to that already existing in the sliver 11 is placed in by the unit 10, and as this sliver 11 is substantially untwisted, the material 12 is substantially untwisted as it is delivered from the rolls 14. The width of the sliver for wrapping is controlled by setting the drawing apparatus to deliver the desired amount of covering material. Should the amount or width of the cover be desired to be wider I may either change the bevel gears 9, 9' to reduce the speed of the delivery rolls, or I may change the pitch of the spiral gears 8, 8' to increase the speed of the receiving rolls, or I may do both; while the other drafts may be changed if desired by changing the gear ratio of the unit shown in Fig. 3 of my Patent No. 1,922,949, above mentioned (for example, the gear 39 of this Patent No. 1,922,949 at the end of its 50 swinging arm).

The core 13 is packaged in a carrier frame which I designate generally as 15, and is shown in Figure 1 and on an enlarged scale in Figure 3. With reference to this Figure 3, a support 16 is 55

shown providing a bearing 17 in which a sleeve 18 is rotatably mounted. This sleeve 18 has fixed thereto a gear 19 by means of a key 20 at one end, while a gear 21 is formed as a part 5 of the sleeve at the other end thereof. Rotatably mounted within this sleeve is the hub 22 having a gear 23 formed at one end thereof, this hub 22 being rotatable with reference to and 10 independent of the sleeve 18. At the other end of the hub 22 there is a shaft 24 which is fixed to the hub 22 to rotate therewith, and upon this shaft 24 I have mounted a spool 25 of a package 6 of the core material 13. This package is held against the shoulder 27 on the shaft 24 by 15 a spring 28 acting through washer 29, the tension of which spring may be adjusted by means of a nut 30 threaded onto the reduced portion 31 of an extension of the shaft 24, the entire package is enclosed within a cylinder 32 which 20 is secured to a disc 33 fixed onto the hub 22 by means of a set screw 34.

A pair of feed rolls 34, 35 are mounted to turn in fixed bearings 36 secured on the gear 23. These rolls nip the core and rotate about their 25 own axes in the bearings 36 and are turned bodily on the line of travel of the core 13 as a center by rotation of gear 23, thus feeding and at the same time revolving the core. In order that these rolls 34 and 35 may be driven, I have 30 provided a worm gear 37 upon the end of a shaft of the roll 34 and a worm 38 engaging this worm gear, which is provided with a shaft 39 extending through the gear 23 and provided with a spur gear 40 engaging the gear 21 on the sleeve 18, thus a relative movement between the sleeve 18 and the hub 22 will cause rotation of the feed rolls 34 and 35.

The carrier frame 15, as a whole, is turned by a gear 41 engaging gear 23 to drive the hub 22 and the package and its housing cylinder 32. This gear 41 is mounted on shaft 42 which is driven by any suitable means as 41', which also 40 drives the spinning unit 10. The gear 19 is also driven from shaft 42 through gear 43, gear 44, shaft 45, and gear 47, which latter gear 47 meshes with gear 19 secured to the sleeve 18 through which the drive for the feed rolls is accomplished. The gear 44 may be changed to 45 provide a different ratio so that the sleeve 18 and hub 22 will be driven at different relative speeds to afford the desired feed to the rolls 34 and 35.

These feed rolls 34 and 35 draw the core 13 through the guide tube 50 mounted within the cylinder 32 and extending through the hollow portion of hub 22 to feed the core 13 axially along the center of the carrier frame. As it emerges from the feed rolls 13, the core may pass through a tank 51 provided with a brush 52 to apply an adhesive thereto, or to perform other desired operation upon the core. It then passes through a guide 53 on one side of the point of delivery of the covering material 12 and then after covered, through guide 54. On the other side of the covering material 12 and the covered core is taken up by a set of feed rolls 56 which are a part of the carrier frame designated generally 58 and which is of substantially duplicate construction to the carrier just described, so far 60 as the differential feed and rotation thereof are concerned. A package 60, however, is not carried by the carrier 58, but it is rather mounted upon a shaft 61 held against spring 62 by a nut 63. This shaft is mounted in a standard 64 70 which is a part of a slide 65 and reciprocated 75

bodily by means of a cam 66 driven through bevelled gears 67 and 68 from a suitable source of power and engaging the follower roll 71, the entire slide being operated in the base 69 so as to traverse the package 60 with reference to the delivery tube 70 through which the covered material is passed.

In feeding a rubber core through the apparatus, I will drive the feed rolls 34 at a speed greater than the feed rolls 34 and 35 so as to provide a stretch and tension upon the core as it is fed, the ratio being something as two to one so as to provide a stretch and a greater delivery in yardage than that supplied, which may be readily accomplished by my differential drive 15 for each of the carrier units.

When covering a rubber core, it is desirable that there be a differential drive for each set of feed rolls; however, where a non-elastic core is to be covered, such for instance as wire, I may 20 use a modified form of apparatus, such as I have shown in Figure 5. In this showing in Figure 5, a spinning unit as before mentioned is designated 10, with the parts thereof indicated by corresponding reference characters in this figure. 25 The carrier frames, however, are different as is also the drive for one of the carriers. One carrier frame in this modified construction is designated generally 75 and consists of a suitable base 76 mounted upon a driven gear 77. From 30 this base 76 there extend outwardly arms 78 and 79 provided with the fixed center 81 and movable center 82 between which there is mounted the core package 80. This movable center is resiliently pressed by means of a helical spring 83 35 operated through a handle portion 84 and slideable through an enlarged bearing 85. The core material 86 is packaged upon the spool 80 and drawn therefrom through the hollow center of the hub 87 of the gear 78 which is rotatably 40 mounted in the bearing 88 at the upper end of support 89.

The other carrier upon which the covered material is packaged, consists of a frame-like structure 90 having a trunnion rotatably mounted in 45 bearing 91 on L-shaped arm 92 and a sleeve-like hub rotatably mounted in bearing 93 supported by the standard 94. This carrier frame has mounted therein a packaging spool 95 mounted upon the driven center 96 and held in position by the movable center 97, which latter is of duplicate construction of the center 82, above described. Within this carrier frame there are a pair of feed rolls 98 suitably mounted upon 50 shafts 99 and a traverse motion designated generally 100, both of which feed rolls and traverse motion are driven through spiral gears 101 and 102 from the shaft 103 which in turn is driven by gear 104 as the carrier frame moves relative to the gear 105. The packaging spool 95 is driven 60 through pulley 106 from pulley 107 on shaft 99 by belt 108 for rotating the driven center 96 which has locking engagement with the spool 95. The belt will slip on pulley 106 as the size of the package increases.

A drive shaft 109 is mounted in bearings in the standards 99 and 94, and through gear 110 engaging the gear 77 drives the carrier 15. The frame 90 is also driven from shaft 109 by means of gear 111 engaging gear 112 which is fixed to 70 the hub of frame 90. In order that there may be a differential drive for the packaging mechanism with reference to the rotation of the frame, gear 105 is mounted on a hollow shaft 113 through which the work passed and which is rotatably 75

mounted within the hub of the carrier frame, and on this hollow shaft there is mounted a gear 114 which meshes through a train of gears similar to that illustrated in Figure 4 connected with 5 a gear 115 secured to shaft 109 and by suitable change gear mechanism, as described in connection with the train of gears shown in Figure 4, I permit of variation in the drive with reference to the rotation of the carrier frame. This shaft 10 109 is driven from any suitable power, such as gear 115 mounted thereon, or from any other suitable source when deriving the power desired.

By the use of my spinning apparatus, I may control the untwisted delivered fibers both as to 15 the quantity of delivered fibers so as to control the width of the ribbon which is wrapped around the core, and I may also control the speed of the delivery of the covering material so that it will be wrapped on the core with more or less 20 tension, as desired. Also, by regulating the speed of advancing of the core, I may regulate the amount of lap of each of the wrappings which is to be had, and may also by regulating the speed of rotative movement of the core about its path 25 of travel regulate the quantity and wrapping, and thus by these various controls I may determine the character of the covering which I place on the core which has heretofore not been possible to such controlled extent with untwisted fibers. 30 The foregoing description is directed solely towards the construction illustrated, but I desire it to be understood that I reserve the privilege of resorting to all the mechanical changes to which the device is susceptible, the invention being 35 defined and limited only by the terms of the appended claims.

I claim:

1. In a covering apparatus, a pair of carrier frames each having feed rolls, means for driving 40 the carrier frames at the same rotative speeds and means for driving the feed rolls of the heads at different feeding speeds, whereby to tension the core of the covered material.

2. In a covering apparatus, a pair of carrier 45 frames, each having feed rolls, means for driving the carrier frames at the same rotative speeds and means for driving the feed rolls of the heads at different feeding speeds, whereby to tension the core of the covered material, and change 50 gears for adjusting the feed with reference to the rotation of the carrier frame upon which the feed rolls are mounted.

3. The method of controlling a covering for a core, which consists in drawing the covering and 55 without twisting delivering it to the core and helically winding it thereon by axial and rotative movement of both ends of the core, and governing the width of delivery of the drawn covering.

4. The method of covering a core, which 60 consists in delivering a narrow strip of untwisted fibers to the core and winding the same thereon by axial and rotative movement of both ends of the core, and governing the width of each wrap by the amount delivered.

65 5. The method of covering a core, which consists in delivering a narrow strip of untwisted fibers to the core and winding the same thereon by axial and rotative movement of both ends of the core, governing the width of each wrap by the amount delivered, and utilizing a differential drive for turning and advancing the core to be covered.

70 6. In combination with means for feeding a filament to be covered, means for rotating both

ends of said filament about its path of travel as an axis, and a drawing apparatus adapted to deliver a coherent strip adjacent said filament and at a large angle thereto whereby the rotation of the filament rolls the strap material thereon. 5

7. The method of covering a core, which consists in feeding such core longitudinally and simultaneously rotating both ends of the same about its path of movement as an axis, reducing a sliver of untwisted fibers to form a coherent 10 strip therefrom, feeding such strip directly to said core at a wide angle thereto and wrapping said strip about said core solely by the rotative movement of the core.

8. In a covering apparatus, a pair of rolls for feeding and a pair of rolls for taking up a filament to be covered, means including a differential drive connection for revolving said rolls about the filament as an axis and rotating the rolls for feeding the filament, and means including a differential drive connection for revolving said take up rolls about the filament as an axis and rotating said rolls for taking up the filament. 15

9. In a covering apparatus, a pair of rolls for feeding and a pair of rolls for taking up a filament to be covered, means for rotating said filament about its path of travel as an axis, means for rotating said delivery rolls, and means for rotating the take-up rolls faster than said delivery rolls in a definite positive relation. 20

10. In a covering apparatus, a carrier having a supply package of filament therein at one side of said apparatus and a carrier having a delivery package for assembling the covered filament at the other side of said apparatus, means for feeding a filament from said supply package and means for delivering said filament to said delivery package and at the same time stretching it, a supply of covering material, and means for rotating said packages and feeding means to rotate said filament and wrap the covering material thereon. 25

11. In a covering apparatus, a carrier having a supply package of filament therein at one side of said apparatus, a carrier having a delivery package for assembling the covered package at the other side of said apparatus, means for feeding a filament from said supply package and means for delivering said filament to said delivery package and at the same time stretching it, a supply of covering material, means for rotating said packages and feeding means to rotate said filament and wrap the covering material thereon, and traverse means for laying the covered filament on said delivery package. 30

12. The method of forming a covered elastic yarn which consists in wrapping relatively non-twisted fibers in a helical path about an elastic core by turning both ends of the core so as to so 35 coherently arrange the fibers as to limit the extension of the core.

13. The method of covering the core which consists in delivering non-twisted fibers to an advancing core of elastic material at substantially right angles thereto and turning both ends of the core to assemble the fibers thereon in a helical path. 40

14. In combination with means for feeding a filament to be covered, means for rotating both ends of said filament about its path of travel as an axis, and a drawing apparatus adapted to deliver a coherent strap of fibers adjacent said filament and at substantially a right angle 45

75

thereto whereby the rotation of the filament rolls the strap material thereon.

15. In combination with means for feeding a filament to be covered, means for rotating both ends of said filament about its path of travel as an axis, a drawing apparatus adapted to deliver a coherent strap of fibers adjacent said filament

and at a large angle thereto whereby the rotation of the filament rolls the strap material thereon, and spaced guides adjacent either side of the position of the delivery of the covering to the filament for maintaining said filament in position. 5

THOMAS HARRIS.
